US00D850733S

(12) **United States Design Patent** (10) **Patent No.:** **US D850,733 S**
(45) **Date of Patent:** **** Jun. 4, 2019**

(54) **STOP BARKING DEVICE**

(71) Applicant: **Fuliang Dong**, Shenzhen (CN)
(72) Inventor: **Fuliang Dong**, Shenzhen (CN)
(**) Term: **15 Years**
(21) Appl. No.: **29/636,756**
(22) Filed: **Feb. 11, 2018**
(51) LOC (11) Cl. **30-04**
(52) U.S. Cl.
USPC **D30/152; D30/199**

CLAIM

The ornamental design for a stop barking device, as shown and described.

DESCRIPTION

FIG. 1 is a front view of a stop barking device;
FIG. 2 is a back view thereof;
FIG. 3 is a top plan view thereof;
FIG. 4 is a bottom plan view thereof;
FIG. 5 is a left side view thereof;
FIG. 6 is a right side view thereof;
FIG. 7 is a perspective view thereof;
FIG. 8 is an enlarged partial front view of the device taken from the showing in FIG. 1;
FIG. 9 is an enlarged partial rear view of the device taken from the showing in FIG. 2;
FIG. 10 is an enlarged partial top view of the device taken from the showing in FIG. 3;
FIG. 11 is an enlarged partial bottom view of the device taken from the showing in FIG. 4;
FIG. 12 is an enlarged partial left side view of the device taken from the showing in FIG. 5; and,
FIG. 13 is an enlarged partial right side view of the device taken from the showing in FIG. 6.
